UNITED STATES PATENT OFFICE

143,094

DESIGN FOR A CUTTING MACHINE

William A. Phllis, Warren, Ohio, assignor to
Beaver Pipe Tools, Inc., Warren, Ohio, a cor-
poration of Ohio

Application June 26, 1945, Serial No. 120,347

Term of patent 14 years

(Cl. D54—14)

To all whom it may concern:

Be it known that I, William A. Phllis, a citizen of the United States of America, residing at Warren, county of Trumbull, State of Ohio, have invented a new, original, and ornamental Design for a Cutting Machine, of which the following is a specification, reference being had to the accompanying drawings, forming a part thereof:

In the drawings, Fig. 1 is a perspective view of a cutting machine embodying my new design

looking from a position adjacent the left rear corner; Fig. 2 is a perspective view of the same looking from a position adjacent the left front corner; and Fig. 3 is an end elevation on a larger scale looking at the right hand end of the machine.

I claim:

The ornamental design for a cutting machine, as shown.

WILLIAM A. PHILLIS.
